UNITED STATES PATENT OFFICE.

THOMPSON W. BLACK, OF MILWAUKEE, WISCONSIN, ASSIGNOR TO MARBLE MOSAIC COMPANY, OF MILWAUKEE, WISCONSIN, A CORPORATION OF WISCONSIN.

METHOD OR PROCESS OF PRODUCING MOSAICS.

1,099,837.

Specification of Letters Patent.

Patented June 9, 1914.

Application filed July 14, 1913. Serial No. 778,860.

To all whom it may concern:

Be it known that I, THOMPSON W. BLACK, a subject of the King of Great Britain, residing at Milwaukee, in the county of Milwaukee and State of Wisconsin, have invented certain new and useful Improvements in Methods or Processes of Producing Mosaics, of which the following is a specification, reference being had to the accompanying drawings, forming a part thereof.

This invention relates to mosaics for ornamental and building purposes and the objects of the invention are to produce such mosaics cheaply and of a solid, substantial and lasting character in the manner to be more specifically described in this specification and claimed.

By the term "mosaic" which I use in the generic sense, I mean any and all kinds of artificially agglomerated material of the general nature of an artificial stone which in the completed product presents a variegated surface whether the surface is varicolored or not.

The known methods of producing mosaics are expensive for two reasons, viz: the care required in preparing the blocks or pieces, and the labor required to set the blocks or pieces in the base or binder, such labor being performed manually. Manual labor is expensive and slow especially where the blocks or pieces of mosaic work have to be separately embedded in a base or binder. Moreover, it is difficult to securely and firmly set the blocks or pieces in the binder or base by hand so that the binder sticks to all the embedded parts of the blocks or pieces.

My invention overcomes the present difficulties in this art because time and labor are reduced to the minimum. The blocks or pieces require no preliminary shaping nor any manual placing. Pieces of material, such as marble, for example, if obtainable of approximately the desired sizes can be used without any preparation whatever. Ordinarily, however, in actual manufacture, it will be found to be cheaper, as well as actually necessary, to crush the material obtainable in a rock crusher of some suitable kind to approximately the size it is desired to use, and the roughness or irregularities of the surfaces of the blocks or pieces does not matter for reasons to be presently explained.

The gist of my invention consists in molding or casting the blocks or pieces, mixed

throughout the body of a suitable binder, in suitable molds or forms and then cutting or sawing through the conglomerate mass so formed to provide the substantially smooth, exposed surface of the mosaic, which may then be polished, if desired, in any preferred manner.

Referring to the drawings which accompany this specification and form a part hereof, Figure 1 is a diagrammatic illustration, in perspective, of a molded or cast mass of my conglomerate mosaic material showing how such a mass may be sawed into slabs, for example; Fig. 2 is a perspective view of a part of a slab sawed or cut from a mass such as that shown by Fig. 1, for example; Fig. 3 is a view similar to Fig. 1 illustrating the possibilities of adaptation of the invention; Fig. 4 is a perspective view of a part of a slab cut from the mass illustrated by Fig. 3; and Fig. 5 is a perspective view of a mold.

In the manufacture of my mosaic, marble or other suitable material or materials may be crushed in a stone crusher and the crushed material may then be mixed with any suitable binder as, for example, cement and water, in a concrete mixer. The resulting batch of conglomerate may then be poured into a suitable form or mold to set and after it is sufficiently hardened it may, if desired, be removed from the form or mold to more completely or to completely harden. The next step in the process is to cut or saw the molded mass so as to cut into or through both the binder and the pieces of marble, or other material or materials, embedded therein so as to produce a mosaic surface. Any pitting of the surface caused by the cutting or sawing can then be smoothed with cement or binding material and the surface polished.

On the drawings, the reference numeral 1 designates a molded or cast mass of the conglomerate which has been subdivided by saw cuts 2 into slabs 3.

The reference numeral 4 designates the binder and 5 the pieces of marble, or other material or materials, embedded in the binder.

The front face of the part of the slab shown by Fig. 2 shows the completed mosaic.

The binder may be colored in any selected manner and the pieces embedded therein may be of the same or of different colors.

Figured effects may be readily obtained by placing in the mold or form for the mass supplemental forms or molds and filling the supplemental molds with mosaic material of contrasting appearance as compared with the body of the mosaic. Preferably this result is accomplished by using thin metal molds or forms, open at the ends, as shown by Fig. 5 of the drawings, of the cross sectional shape of the figured effect desired. The form or mold is filled with the mosaic material and the supplemental forms or molds are filled with contrasting mosaic material and then the supplemental forms or molds are withdrawn before the binder sets so that the different parts of the mass join together to form a single mass. If desired the supplemental molds or forms may be left embedded in the mass instead of being withdrawn.

Fig. 3 of the drawings illustrates a mass of mosaic similar to that shown by Fig. 1 except contrasting material has been molded in the mass by supplemental molds like that illustrated by Fig. 5 of the drawings. Fig. 4 of the drawings shows clearly how the contrasting material runs through a slab and the mass in the selected figured shape.

By mixing the blocks or pieces with the binder they are thoroughly incorporated and mixed with the binder so that they are firmly cemented in position thereby not only producing a solid mass but also insuring against their being torn out of the binder while the cutter or saw is at work on them.

While for simplicity of illustration I have shown merely masses of the conglomerate and slabs cut therefrom, it should be understood that the conglomerate may be molded in any form desired and then so much of the surface or surfaces cut or sawed off to cut into the pieces embedded in the binder to produce the mosaic surface desired. The mere molding is not sufficient to produce the

desired results because sufficient area of embedded pieces would not show as will be readily understood but the part to be cut or sawed off to obtain the desired surface effect will depend on the character of the molded mass and may be little or much and may become waste or not. In the drawings I have illustrated a method of obtaining slabs with little waste.

The mosaic produced by this method is a very striking and handsome material which can be used for all ornamental and building purposes for which its character renders it suitable, as, for example, tiles, floors, walls, ceilings, columns, etc.

What I claim is:

1. The method or process of producing mosaic which consists in mixing pieces of material throughout the body of a binder and then forming a surface by cutting through the binder and the pieces embedded therein.

2. The method or process of producing mosaic which consists in mixing pieces of material throughout the body of a binder, molding the conglomerate mass thus obtained, allowing the mass to harden and then forming a surface by cutting through the binder and the pieces embedded therein.

3. The method or process of producing mosaic which consists in mixing contrasting masses each composed of pieces of material mixed throughout the body of a binder, molding the contrasting masses into a design, and forming a surface by cutting through the binder and the pieces embedded therein in a plane intersecting the division between the contrasting masses.

In witness whereof I hereto affix my signature in presence of two witnesses.

THOMPSON W. BLACK.
